UNITED STATES PATENT OFFICE.

IRVING F. AVERY, OF CHICAGO, ILLINOIS, ASSIGNOR TO JACOB H. PRESS, OF CHICAGO, ILLINOIS.

DUMP-WAGON OR THE LIKE.

1,334,730.

Specification of Letters Patent.

Patented Mar. 23, 1920.

Application filed December 27, 1915. Serial No. 68,769.

To all whom it may concern:

Be it known that I, IRVING F. AVERY, a citizen of the United States, residing at Chicago, in the county of Cook and State of Illinois, have invented certain new and useful Improvements in Dump-Wagons or the like, of which the following is a description.

My invention belongs to that general class of devices known as dump wagons, and relates particularly to a wagon or truck having a body arranged to be tilted or elevated so as to discharge the load at a desired point in a minimum time and with a minimum of labor. The invention more particularly relates to improved mechanism for tilting the body or lowering it back to carrying position. The invention has among its objects the production of a device of the kind described that is simple, convenient, durable, efficient and satisfactory, that may be used wherever found applicable. The invention also includes an improved form of body arranged to normally incase the hoisting mechanism and protect it against injury or against action of the elements, the construction being such that the capacity of the body is increased rather than decreased. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

Figure 1 is a side elevation of one form of my device applied to a motor truck;

Fig. 2 is a sectional view taken substantially on line 2, 2 of Fig. 3;

Fig. 3 is a sectional view taken substantially on line 3, 3 of Fig. 4;

Fig. 4 is a view in elevation taken substantially on line 4, 4 of Fig. 1;

Fig. 5 is a view similar to a portion of Fig. 1, with the body raised to dumping position;

Fig. 6 is a sectional view taken substantially on line 6, 6 of Fig. 4;

Fig. 7 is a sectional view taken substantially on line 7, 7 of Fig. 6;

Fig. 8 is a sectional view taken substantially on line 8, 8 of Fig. 5;

Fig. 9 is a view similar to a portion of Fig. 5, showing a slightly modified construction;

Fig. 10 is a sectional view taken substantially on line 10, 10 of Fig. 9, and

Fig. 11 is a sectional view taken substantially on line 11, 11 of Fig. 10.

Referring to the drawings, 1 represents the vehicle frame or chassis supported by wheels 2 and 3, or their equivalents for the purpose. It may be mentioned in this connection that while a four-wheel truck is shown, the forward end of the chassis frame might be suitably carried from a tractor or truck, the same constituting a trailer, or the vehicle might be merely a four-wheeled trailer to be drawn by a tractor truck or other motive power. Arranged on the vehicle is a body 4, which is carried by the supporting frame parts 5 and cross beams 6. The body and its frame are suitably pivotally or tiltably carried by the vehicle. In the construction shown the side parts 5 of the body frame are pivotally supported and secured to the vehicle frame at 7. It is, of course, obvious that any style or type of body 4 may be employed, that shown being merely for illustration.

In the preferred embodiment of the invention, the body is elevated or lowered, by means of a hydraulic hoist, which is pivotally carried from the frame 1, as will be hereafter described.

The hydraulic hoist shown consists of an outer casing 8, from the top of which projects a plunger rod 9. The hydraulic casing 8 is supported on the frame 1 by the cross beams 10 and 11 (see Fig. 6). As shown, brackets 12 are supported on the base piece 10, and the angle 13 carried by the beams 10 and 11, the several parts being secured together in any desired manner. The casing 8 is formed with a T-shaped lower end terminating in trunnions or bearings 15. The casing or cylinder may be connected with the pumping mechanism in any suitable manner. Extending through one side of the base trunnion (see Fig. 7) is a duct 16, communicating with the chamber 17 in the casing 8, at the lower side of the plunger 18, which carries the plunger rod 9. The duct 16 is connected by means of pipe 19, or the equiva-

lent, with the pumping system, the hoist being a hydraulic operated and controlled hoist, as previously referred to. From the upper end of the chamber extends a pipe 20, 5 which is connected with duct 21 in the opposite side of the base, and this is connected by pipe 22, or the equivalent, with the pumping mechanism. It will be noted that the two pipes 19 and 21 being connected at the base, 10 as shown, the movement of the hoist at that point is merely pivotal or rotatable. The pipes are suitably connected to the base in any preferred manner, so that the hoist is free to tilt or pivot without movement of the 15 pipes, suitable stuffing boxes being employed. It is not considered necessary to illustrate or describe in detail the stuffing boxes, as these may be as preferred, as long as they are suitable for the purpose, and in case flexible conductors are used connected to the casing, the 20 stuffing boxes would not be required at the base.

Arranged at the upper end of the plunger 9 is a head 25, which is formed with shaft 25', upon which are arranged the sheaves or pulleys 26, over which extend the cables 27, or their equivalents. One end of each of the cables 27 is secured to the brackets 28, which are suitably secured to 30 the beams 6 at the front of the body or its frame. The cables 27 may be provided with terminals 29 (see Fig. 3) for convenience in fastening the same to the brackets 28. The opposite ends of the cables are suitably connected to the vehicle frame 1, or the equivalent. As most clearly shown in Fig. 8, 35 cables 27 are connected to a bar 30, and this is connected by means of rod 31, 32 and turnbuckle 33 to a bracket 34, secured to 40 the cross beam 11. (See Figs. 6 and 8). The turnbuckle permits adjustment of the parts. As is obvious, as the plunger 18 is 45 raised, raising the plunger rod 9, and head 25, the forward end of the body, to which is secured one end of each of the cables 27, 50 is raised, the opposite ends of the cables being fixed at the base of the hoist. The head 25 is suitably connected with the body, as will be hereafter described, so that as the body is raised, the hoist is tilted with and toward it, for the reason mentioned.

Arranged at the rear of the hoist, and at the forward end of the body 4, is a barrier or wall 36, the same being preferably provided with sides 37 and top 38, the same forming a casing or housing about the hoist when the body is down, as shown in Fig. 1. It is not necessary, however, for the housing to be the full width of the body; consequently the sides of the body may be extended to the forward end of the housing, and the cross wall or end partition 39 provided. This affords considerable additional carrying space at each side of the hoist, and 65 at the same time the hoist is practically

completely incased on three sides and the top protected. The rear end of the cab may be partitioned, so that the forward end of the hoist is inclosed when the same is in the position shown in Fig. 1.

As most clearly shown in Figs. 1, 2, 3, 4 and 5, arranged within the housing and carried by the wall 36 are a pair of guides 40, or their equivalents, it being readily understood that channels or the equivalent 75 would serve the purpose of the I beams shown. The head 25 carries rollers 42 arranged to co-act with the guides, and, as shown, it is formed with extending parts 41, carrying a shaft 43, upon which are arranged the rollers 42, or their equivalents, 80 arranged to engage with the beams or guides 40. The guides 40 shown are preferably curved slightly backward at the upper end 85 in some cases (as shown) and in other cases at the bottom, or at both top and bottom, so that the hoist stands substantially vertically when the body is down and works smoothly. This, however, is a matter of design, depending upon the sizes and construction of the 90 parts, etc., as in some cases straight guides are satisfactory for the purpose.

The operation of the device may be briefly described as follows: Assuming that the body is down, as shown by Fig. 1, if the pump or the equivalent is operated so as to raise the plunger 18, or its equivalent, the head 25 is raised, owing to movement of the plunger rod 9. The head being raised and the ends of the cables 27 being secured to the vehicle frame, as previously described, the length of the part of the cables between the brackets 28 and the sheaves 26 is shortened, causing the body to be raised. As the forward end of the body rises, it draws 100 the head 25 over, tilting the hoist. The object and advantage of the tilting of the hoist may best be understood by referring to Fig. 5. Referring to this figure, it will be noted that there is no transverse strain on 110 the plunger rod 9 or the casing 8, but that the ends of the cables 27 and the plunger rod 9 are substantially parallel at all times; consequently all power applied is utilized 115 for moving the load without transverse strain on the hoist. To drop the body the hydraulic mechanism is controlled so that the plunger settles back, the weight of the body causing it to drop, and at the same time move the hoist back to vertical position.

A slightly modified construction of device is shown in Figs. 9, 10 and 11, the difference being in the mechanism for tilting the hoist simultaneously with the tilting of the body. 125 Referring to these figures, 46 represents the vehicle frame pivotally carrying the body 47, only a portion of the body and vehicle being shown. The casing 48 is pivoted to the frame at 52 similar to the other con- 130

struction, 49 being the plunger rod carrying the head 53. The cables 51 extend over the sheaves 50, and in so far as described the device is similar to the other construction.

5 In this case, however, guides 56 are arranged on the side of the casing 48, and arranged to slide on the guides are blocks 55 of any suitable design. These blocks are connected with the head 53 by the bars 54, and connected with the vehicle frame by bars 58, the same being pivotally secured to the blocks by the bolts 57, and to the frame at 10 59. With this construction as the head 53 is raised it raises the blocks 55 through the 15 rod 54, thereby raising the forward end of the bars 58. As these are raised the same draw the casing 48, or, that is, draw the hoist to an inclined position, so that the pulling or strain on the cables 51 is parallel with 20 the plunger 49. The blocks 55 may be maintained on the guides by passing a bolt through the bars or members 58, as shown, or in an equivalent manner.

As before stated, it is immaterial upon 25 what style of truck or vehicle the hoist is mounted, and it is likewise immaterial as to the particular style of body carried upon it. With either construction there is no bending or transverse strain on the hoist. It will be 30 noted by referring particularly to Fig. 1, that the forward end of the body 4 may extend up close to the cab in this construction. Ordinarily the bodies are cut off substantially at a point in alinement with the wall 35 36 of the hoist housing. I have not considered it necessary to illustrate in detail any of the hydraulic apparatus, such as the pump or method of controlling the same, as any style of pumping mechanism or the like may 40 be employed.

Having thus described my invention, it is obvious that various immaterial modifications may be made in the same without departing from the spirit of my invention; 45 hence I do not wish to be understood as limiting myself to the exact form, construction, arrangement or combination of parts herein shown and described, or uses mentioned.

50 What I claim as new and desire to secure by Letters Patent is:—

1. In a vehicle of the kind described and in combination a body carried on the vehicle and pivotally secured thereto substantially adjacent the rear end thereof, tilttable hoisting mechanism arranged at the forward end of the body of said vehicle and operatively connected with the body, a guide member arranged at the front end of said 55 body, means carried by the hoisting mechanism coöperating with the guide, comprising a rearwardly extending arm provided with a roller thereon, said guide being arranged to engage said roller on the opposite 60 sides thereof.

2. In a vehicle of the kind described and in combination, a body pivotally secured thereto substantially adjacent the rear end thereof, tilttable hoisting mechanism arranged at the forward end of the body on 70 said vehicle, and operatively connected with the body, a pair of guides arranged on the front end of said body, and extending upwardly and rearwardly at their upper ends, rolls arranged to engage said guides, and 75 means carried by said hoisting mechanism for carrying said rolls.

3. In a vehicle of the kind described and in combination, a body carried on the vehicle and pivotally secured thereto substantially 80 adjacent the rear end of the vehicle, hydraulic hoisting mechanism arranged at the forward end of the body on said vehicle and including a substantially vertically movable plunger rod, said body of sufficient length to 85 extend past the hoisting mechanism on each side thereof, said body provided with housing arranged to substantially inclose the hoisting mechanism at the side, rear and top when the body is in carrying position upon 90 the vehicle, a pair of guides arranged within said housing at the rear of the hoisting mechanism, and carried by the rear wall of said housing, means carried by said plunger rod for engaging said guides whereby the 95 tilting of the body will automatically tilt the hoisting mechanism.

4. In a vehicle of the kind described and in combination, a suitable body pivotally carried on the vehicle, hoisting mechanism arranged at one end of said body, and including a casing, a plunger contained therein and a plunger rod projecting from the upper end of the casing, means for operatively connecting said plunger rod with said body, including a cable, and means for tilting the casing upon the tilting of the body to maintain the said cable substantially parallel with said plunger rod, comprising a guide arranged on said body at the rear of 100 said casing, and means carried at the upper end of said plunger rod for engaging said guide whereby upon the upward tilting of the adjacent end of the body, the casing head will be tilted toward the body. 110

5. In a vehicle of the kind described and in combination, a body tiltably mounted on the vehicle, means for tilting said body comprising a hoist consisting of a casing pivotally secured to the vehicle on an axis transversely thereof, and having a plunger with a plunger rod projecting upwardly from the top of the casing, said plunger rod provided with a head at its upper end, with a shaft at each side thereof, a sheave arranged at each side of said rod, and rotatably carried by said shafts, cables extending over said sheaves with the ends thereof on each side of the sheaves extending parallel with the plunger rod at the front and rear thereof, 125 130

- one end of each cable secured to the free end of the body at the rear of the casing, means for securing the other ends of the cable to the vehicle, and means for tilting 5 the casing and plunger rod during the upward or downward movement of the plunger during the tilting of the body, whereby the cables are maintained substantially parallel with the rod on both sides thereof.
- 10 6. In a vehicle of the kind described and in combination, a body mounted on the vehicle, and tiltable thereon, means for controlling the tilting of said body, comprising a hoist, consisting of a casing tiltably mounted 15 on the vehicle on an axis parallel with the tiltable axes of the body, a plunger arranged in said casing and provided with a plunger rod projecting upwardly from the top thereof, said plunger rod provided with a head at 20 its upper end with a shaft at each side, a sheave carried by each shaft, cables extending on said sheaves with the ends thereof on each side of the sheaves extending substantially parallel with the plunger rod at the 25 front and rear thereof, one end of each cable secured to the front end of the body at the rear of the casing, means for securing the other ends of the cable to the vehicle, and means for tilting the casing upon movement 30 of the plunger during the raising or lowering of the body, whereby the cables are maintained substantially parallel with the rod on both sides thereof, comprising a pair 35 of guides arranged on the body at the rear of said casing, and extending upwardly, and thence rearwardly at their upper ends, and rollers carried by said head arranged to engage said guides.
7. In a vehicle of the kind described and 40 in combination, a body mounted on the vehicle and pivotally secured thereto on an axis transverse to the vehicle, means for moving said body about its pivotal axis and lifting the front end thereof, comprising a hydraulic hoist consisting of a casing mounted 45 on the vehicle and pivotally secured thereto at its lower end on an axis parallel with the axis of the pivotal connection of the body, a plunger arranged in said casing and provided with a plunger rod projecting upwardly from the top of the casing, said plunger rod having a head at its upper end with a shaft at each side, the axes of said shafts cutting the longitudinal axis of the 50 plunger rod, a sheave arranged on each shaft and rotatably carried thereby, cables extending over said sheaves with the ends thereof on each side of the sheaves extending substantially parallel with the plunger 55 rod at the front and rear thereof, one end of each cable secured to the front end of the body at the rear of the casing; means for 60 securing the other ends of the cable to the vehicle, consisting of a bar secured to the ends of the cables and adjustably secured to the vehicle, and means for moving the casing and plunger rod about its pivotal axis upon movement of the plunger during the movement of the body, whereby the cables are at all times arranged and maintained parallel with the rod on both sides thereof, comprising a pair of U-shaped guides arranged on the front end of the body and extending upwardly, and thence curved rearwardly at their upper ends, arms 65 carried by said head projecting rearwardly adjacent said guides, and rollers carried by said arms arranged to engage said guides.
8. A vehicle of the kind described in combination, a body mounted on the vehicle and 70 tiltable thereon, means for controlling the tilting of said body, consisting of a part tiltably mounted on the vehicle on an axis parallel with the tiltable axis of the body, a member carried by said part projecting 75 upwardly from the body thereof, said member being provided with a head at its upper end and a shaft at each side, a sheave carried by said shaft, cables extending on said shafts with the ends thereof on each side of the 80 sheaves extending substantially parallel with the member at the front and rear thereof, one end of each cable secured to the front end of the body at the rear of the casing, means for securing the other ends of 85 the cable to the vehicle, and means for tilting the movable part upon raising and lowering of the body, whereby the cables are maintained substantially parallel with the member on both sides thereof, said means 90 comprising a pair of guides arranged on the body at the rear of said part and extending upwardly, and thence rearwardly at their upper ends, and rollers carried by said head arranged to engage the guides.
9. In a vehicle of the kind described and in combination, a body pivotally secured thereto substantially adjacent the rear end thereof, a tiltable hoisting mechanism arranged at the forward end of said body and a connection between said hoisting mechanism and the body, a guide arranged on said body and extending upwardly and then rearwardly at its upper end, and means carried by said hoisting mechanism for coöperating 95 with said guide.
- In testimony whereof, I have hereunto signed my name in the presence of two subscribing witnesses.
- IRVING F. AVERY.
